Primary Examiner — Joseph Kukella*Assistant Examiner* — Darryl J Dardenne(57) **CLAIM**

The ornamental design for a drinking water purifier, as shown and described.

DESCRIPTION

FIG. 1 is a front elevation view of a drinking water purifier showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is an enlarged view of the encircled portion in FIG. 8.

The dash-dot-dash lines in FIG. 8 and FIG. 9 represent boundary lines and form no part of the claimed design. The broken lines depict portions of the drinking water purifier that form no part of the claimed design.
